UNITED STATES PATENT OFFICE.

THEO H. PURPLE, OF CONSTANTINE, MICHIGAN.

CURTAIN-STRETCHER.

No. 897,398.

Specification of Letters Patent.

Patented Sept. 1, 1908.

Application filed June 3, 1907. Serial No. 376,954.

To all whom it may concern:

Be it known that I, THEO H. PURPLE, a citizen of the United States of America, and a resident of Constantine, county of St. Joseph, and State of Michigan, have invented certain new and useful Improvements 5 in Curtain-Stretchers, of which the following is a specification.

My invention relates to curtain stretchers, 10 which are also applicable as clothes driers, and has for its object improvements in such devices.

The present device is designed to occupy 15 a small space, to be completely adjustable so as to successfully hold anything from a small piece of lace or cloth up to the widest and longest lace curtain, to be conveniently manipulated, and when not in use to be "knocked down" so that it may be packed 20 away.

In the accompanying drawings, Figure 1 is a side elevation; Fig. 2 is a plan; Fig. 3 is a section on line 3—3 of Fig. 2; Fig. 4 is a detail in end elevation; Fig. 5 is an enlarged detail section showing one of the 25 curtain holding pins and the slot therefor; and Fig. 6 is a perspective view of the pin.

In the said drawings A, A, are two upright standards which are connected together by a cross bar or bridge-tree B. 30 On the cross-bar B are brackets B¹, and running the base of each standard A is a screw A¹. Thumb nuts A² serve to hold the brackets B¹ to the standards A. As the standards A are not rigidly secured together at any other place the mere removal of the thumb nuts A² permits the framework to be taken down.

Supported in a hole in the top of one 40 standard A, and in a slot in the top of the other standard, is a bar or shaft C upon which is mounted a rectangular reel. This reel consists of two end plates D and E, and four connecting bars F. There is also an intermediate plate G provided with a hub G¹, and which is secured at any desired 45 adjustment on the shaft C by means of a set screw G². One of the bars F is cut away, as shown at F¹ in Fig. 3, and in this cut-away portion are a series of fixed pins H. This bar and one or more of the other bars 50 are graduated as shown in Fig. 2. The outside corners of the bars F are given a long round as shown in Fig. 3, the object of 55 which is to prevent the formation of creases in a curtain wound upon the reel.

In addition to the bars so far described there is an independent or separate bar J which is also provided with fixed pins H like those previously described, which pins 60 are located in a cut-away portion J¹ as shown in Fig. 3. On one end of the bar J is an angle plate J², and on the other end is a cam J³. The distance between the plate J² and cam J³ is equal to the distance 65 between the outside faces of the end plates D and E. It will be apparent that the angle plate J² and cam J³ serve as a means for securing the bar J at any desired position 70 on the reel.

The end plate D is provided with a series of holes D¹ (Fig. 4) and secured by a suitable chain to the adjacent standard A is a pin K which passes through a hole in the standard and serves to hold the reel at any desired position. 75 When the pin K is removed the reel is free to rotate on the shaft C. Around the edges of the end plate D and the edges of the intermediate plate G are T-shaped slots T in which are inserted sliding pins M. These 80 pins are bent out of wire so as to have a T-shaped head, as shown in Figs. 5 and 6, and an off-set at the pointed end. These off-sets are turned so that they trail inward toward the center of the apparatus from each of the 85 plates which have the slots T.

In applying a lace curtain to the stretcher the bar J and pin K are first removed. The operator then adjusts the plate G on the shaft C so that the distance between the plates D 90 and G is equal to the width of the curtain. She then hooks one end of the curtain on the pins H in bar F and follows this by hooking the edges (sides) of the curtain on the pins M in plates D and G. In doing this she turns 95 the reel on its shaft C until she comes to the other end of the curtain. She then inserts the pin K to hold the reel stationary, and follows this by attaching the supplementary bar J adjacent to the last end of the curtain. 100 She then secures the final end of the curtain to the hooks or pins H on the bar J.

The reel is usually made of such size that the longest curtain will go about twice around, and of a length sufficient to accommodate 105 the widest curtain. The bar F which holds the pins H, being grooved and the pins being below the outer surface of the bar, the second wrap of the curtain does not strike the pins. The adjustable pins M and their slots are so arranged that the said pins are securely held 110 in proper position while at the same time

they are freely movable lengthwise in their slots. These are characteristics particularly desirable in devices of this kind.

The graduations heretofore mentioned and illustrated in Fig. 2 assist the operator in securing the curtain or a small piece of cloth or lace straight and even so that it will be straight and even when dried. The provision for locking the reel in any desired position is advantageous in manipulating the device when applying the curtain.

When the curtain is in place the stretcher may be set near a stove and the reel secured so as to hold one face toward the stove. The reel may then be turned on its axis so as to present the other face to the fire and be locked in that position.

What I claim is:—

1. In a device of the class described, a reel 20 mounted to rotate upon an axis, said reel being composed of end plates connected together by longitudinal bars, a series of pins secured to one of said bars and serving as a means for holding the end of a curtain, a series 25 of adjustable pins secured to one of said end plates and serving as a means for holding one edge of the curtain, an intermediate plate axially adjustable to any desired position between the end plates, and other adjustable pins secured to the intermediate plate and serving to hold the opposite edge of the curtain.

2. In a device of the character described, 35 a series of parallel bars mounted to rotate about an axis, a series of pins secured to one of said bars and serving to hold one end of a curtain mounted upon said bars, a separate bar arranged to be secured at any desired position with respect to the previously 40 mentioned bars, and a series of other pins secured to said separate bar and serving to hold the other end of the curtain.

3. In a curtain stretcher, a series of parallel bars mounted to rotate about an axis, 45 a series of pins secured to one of said bars and serving to hold one end of a curtain, said pins being so located that they will not be touched by a curtain passing over said bar to the next adjacent bar, and a separate 50 adjustable bar provided with pins for holding the other end of the curtain.

4. In a curtain stretcher, a reel composed of bars upon which a curtain may be wound, one of said bars being provided with a 55 groove, a series of curtain holding pins lo-

cated in said groove as described, and a separate adjustable bar provided with other curtain holding pins.

5. In a curtain stretcher, a reel composed of bars upon which a curtain may be wound in successive layers, curtain holding pins being secured to one of said bars and so located as not to be touched by succeeding layers of the curtain wound upon the reel, and an adjustable device for securing the 65 final end of the curtain.

6. In a curtain stretcher, a series of bars mounted to rotate about an axis and so arranged as to constitute a reel upon which a curtain may be wound, curtain holding devices secured to one of said bars and so arranged as not to touch succeeding layers of curtain wound upon the reel, and an adjustable bar arranged to be secured to the reel over layers of curtain already wound thereon, said adjustable bar being provided with 70 means for securing the final end of the curtain.

7. A curtain holding reel mounted to rotate upon an axis, devices on said reel and 80 located inside of the exterior surface thereof for securing one end of a curtain to be wound upon the reel, other devices arranged to be adjustable to suit the width of the curtain and also arranged to project beyond the exterior surface of the reel so as to engage and hold each successive layer of curtain at the sides thereof, and a removable bar arranged 85 to be secured at any position on the reel over the curtain wound thereon and provided 90 with devices for securing the final end of the reel.

8. In a reel upon which a curtain may be wound for drying or stretching, a bar provided with a series of pins for holding the 95 first end of a curtain wound upon the reel, other pins carried by the reel and serving as means for securing the sides of the curtain as it is being wound upon the reel, and a separate bar arranged to be secured at any 100 position on the reel over the layers of curtains already wound thereon, said separate bar being provided with means for holding the final end of the curtain.

Signed at Constantine, Mich., this 31st 105 day of May 1907.

THEO H. PURPLE.
